[57] CLAIM

The ornamental design for a hanger for trousers, skirts or the like, as shown.

DESCRIPTION

FIG. 1 is a front elevational view of a hanger for trousers, skirts or the like showing my new design;

FIG. 2 is a top plan view;

FIG. 3 is a side elevational view taken from the left of FIG. 1, the side opposite being a mirror image thereof except for the hook which follows the contour shown in FIG. 1;

FIG. 4 is a rear elevation view;

FIG. 5 is a bottom plan view.

Fig. 2.

Fig. 1.

Fig. 3.
